UNITED STATES PATENT OFFICE.

EDWARD W. HILL, OF CHICAGO, ILLINOIS.

LOOSE-LEAF LEDGER.

Application filed April 19, 1921. Serial No. 462,586.

To all whom it may concern:

Be it known that I, EDWARD W. HILL, a citizen of the United States of America, residing at Chicago, Illinois, have invented a new and useful Loose-Leaf Ledger, of which the following is a specification.

My invention relates particularly to binders of a character set forth in my Patent #1,224,465 dated May 1st, 1917.

One object of my invention is to provide an improved and simple form of construction to facilitate the assemblage of the parts of the binder.

Another object is to increase the security of the parts when assembled.

Another object is to keep the parts in their proper relative position when the binder is opened out for the transfer of sheets from one side to the other.

Another object is to facilitate the use of the construction in what is known as machine posting.

Fig. 1 is a perspective view of a binder embodying the improvements of my invention.

Fig. 2 is a perspective view on a smaller scale showing the parts of the binder opened out and arranged for what is commonly termed machine posting.

Fig. 3 is a perspective view showing parts of the binder partially assembled.

Fig. 4 is a perspective view of a connecting clip.

Fig. 5 shows two of the leaf-supporting posts and extensions.

Fig. 6 is a perspective view of two of the post extensions.

A support 10 carries posts such as 11 and 12 and a corresponding support 13 carries complementary posts 14 and 15 adapted to telescope respectively with posts such as 11 and 12 when the parts are assembled in the position of Fig. 1. As shown, the free end of one member of each pair of telescoping posts, as 11 and 15, presents a socket to receive a suitably rounded end of the other member of the pair, as 12 and 14. While it is desirable to alternate the socket and round ended posts on a single support in the manner illustrated in Fig. 2, obviously any other arrangement may be employed so long as each socket ended post telescopes with a post having a rounded end when the binder covers are closed. Covers such as 16 and 17 are preferably hinged to the supports 10 and 13 respectively. The rear sup-

port 10 has secured to it a back member 18 which cooperates with the inner back member 19 carried by the support 13 to position the leaves and hold the parts in their proper relative positions. I describe as the face of each back member 18, 19 that surface which is turned towards the covers 16, 17 when the binder is in normal or closed position as shown in Fig. 1. The surfaces of the back members opposite to the faces I call the backs, i. e. those surfaces which are seen in Fig. 3. In the form shown, the face of back 18 is provided with one or more headed studs or projections 20 whose shanks 70 slidably engage in the slots 21 of the inner back 19 when the parts are assembled with the face of back 18 turned towards the back of back 19 in the position of Figs. 1 and 3. This stud and slot engagement gives substantial security in addition to the telescopic connection of the posts.

At each end of the inner back 19 I preferably provide a flange 22, and these flanges are so located and constructed with relation to the ends of the outer back 18 that they serve as positioning guides in assembling the parts, with the back members face to back as shown in Figs. 3. These flanges also serve as guides in assembling the parts with the back members back to back as shown in Fig. 2.

A plurality of spring-pressed locking pins 23 are carried by the outer back 18 and are adapted to engage in the holes or recesses 24 in the inner back. These pins are adapted to be simultaneously operated by means of a plunger 25 and mechanism such as shown in my former Patent #1,224,465. The back 18 serves as a housing for this mechanism.

When the parts of the binder are assembled back to back as shown in Fig. 2 for the transfer of sheets from one set of posts to the other, they are held in predetermined relative position by means of a clip 26, in the form of a separate member the two sides of which are preferably resilient so as to embrace the back members 18 and 19 and hold them in position. The clip may 105 be provided with a knob or projection 27 to engage in a suitable recess in one of the back members to hold the clip yieldingly in place.

To facilitate the transfer of sheets from the rear post sections 11 and 12 to the front post sections 14 and 15, I preferably pro-

wide pointed extensions 28 and 29 which are adapted to engage the posts 14 and 15. The extensions 28 are tubular at their lower ends to slip over the posts 14 and the rear ends 5 of the extensions 29 are reduced in diameter so as to fit into the ends of the posts 15. The construction of the parts is such that when they are assembled, as shown in Fig. 5, the posts and their extensions are uniform 10 in diameter so that the leaves can be slipped on or off without danger of catching.

The construction is such that the binder and leaves may be used as an ordinary loose leaf ledger for the entry of items by hand 15 and for the insertion and removal of leaves when desired, as set forth in my former patent. In addition, the construction is such that by using the temporary extensions 28 and 29, the transfer of leaves is 20 very greatly facilitated so that the ledger may be used efficiently for machine posting as well as hand posting. After the posting is completed and the parts are in the position shown in Fig. 2, the post extensions and 25 the clip 26 are removed and the parts are assembled as indicated in Fig. 3.

I claim :

1. In a loose leaf binder, a support having 30 posts extending therefrom and a back member, a second support and posts extending therefrom and adapted to telescopically engage the other posts, a back member extending from said second support, headed studs carried by one of said back members, the 35 other back member having slots to receive the shanks of said headed studs and having open ends to permit the supports to be disconnected and placed with their back members back to back for the transfer of loose 40 leaves from the posts of one support to the posts of the other support.

2. In a loose leaf binder, two supports, 45 posts carried by said supports and telescopically engaging each other, back members carried by said supports and extending parallel with said posts, and flanges extending outwardly from the inner back member and adapted to serve as positioning guides in 50 engagement with the ends of the outer back member when the posts are telescopically connected and also when the posts are disconnected and the back members of the binder are placed back to back.

3. In a loose leaf binder, separable supports having leaf-engaging telescopic posts 55 and cooperating back members, and a clip removable from all the other parts for engaging said back members to hold said parts in predetermined relative position independently of said posts and a detent on

said clip to hold the same in effective position.

4. In a loose-leaf binder, front and rear covers including separable back members, telescopic posts carried thereby, means for 65 holding the parts together with said posts in telescopic engagement, and a channel-shaped clip having resilient flanges adapted to frictionally engage the face portions of the back members to hold them in predetermined relative position when assembled back to back.

5. In a loose leaf binder, front and rear covers, telescoping posts carried thereby, means for holding the parts together with 75 the posts in telescopic engagement, detachable extension members adapted to engage some of said posts when the posts are disconnected, and detachable means independent of said posts and independent of said 80 extensions for holding the parts of the binder in predetermined relative position to prevent the posts from being brought into alignment when said extensions are in place.

6. In a loose leaf binder, front and rear members having cooperating leaf-supporting members, back members placed face to back along one edge of the binder and having slot and stud connections and variably 90 operable interlocking pins and holes for holding the parts together.

7. In a loose-leaf binder, front and rear members having cooperating leaf-supporting members, back members carried by said 95 front and rear members and having slot and stud connections and interlocking members for holding said front and rear members together, and a detachable clip having resilient flanges for holding said front and 100 rear members in predetermined relative position when said back members are assembled back to back.

8. In a loose-leaf binder, front and rear members having cooperating leaf-supporting members, separable back members carried by said front and rear members and having slot and stud connections and interlocking members for holding said parts together, other means independent thereof for holding the parts of the binder in predetermined relative position when said leaf-supporting members are separated and the back members assembled back to back, and extension members cooperating with some of 105 said leaf-supporting members and independent of the interlocking members, serving to facilitate the transfer of sheets from the other leaf-supporting members.

EDWARD W. HILL.
